UNITED STATES PATENT OFFICE.

STEPHEN N. SMITH, OF PROVIDENCE, RHODE ISLAND, ASSIGNOR TO THE UNION EYELET COMPANY, OF SAME PLACE.

MACHINE FOR SETTING LACING-HOOKS.

SPECIFICATION forming part of Letters Patent No. 602,881, dated April 26, 1898.

Application filed June 13, 1896. Serial No. 595,386. (No model.)

To all whom it may concern:

Be it known that I, STEPHEN N. SMITH, a citizen of the United States, residing at Providence, in the county of Providence and State 5 of Rhode Island, have invented certain new and useful Improvements in Machines for Setting Lacing-Hooks; and I do hereby declare the following to be a full, clear, and exact description of the invention, such as will 10 enable others skilled in the art to which it app pertains to make and use the same, reference being had to the accompanying drawings, and to letters of reference marked thereon, which form a part of this specification.

15 My present invention relates to machines for setting or attaching lacing hooks or studs to boots and shoes, the invention being an improvement on the machine patented September 18, 1894, No. 526,295. In said patent 20 entered machine for setting lacing-hooks the setting die or spur on which the work or material is placed during the setting operation is moved up and down with respect to the anvil, the latter forming a stud feeding and 25 spacing wheel adapted to be rotated intermittently. An objection to said patented machine, as well as to other analogous machines having vertically-reciprocating setting-dies, is that its capacity or efficiency is materially 30 lessened owing to the fact that the attendant or operator, even though a skilled one, cannot always properly place the work in position with sufficient accuracy upon the moving die when the machine is driven by power 35 at a comparatively slow speed. I would state that in shops or factories devoted to the manufacture of shoes the setting of the lacing hooks or studs is usually done by employees who work by the piece or case. Therefore the 40 amount of their wages is to a great extent dependent upon the rate of speed at which the setting-machines may be successfully operated.

The object I have in view is to provide machines of the type above referred to with 45 means whereby they may be operated more rapidly and at the same time with greater efficiency, the percentage of imperfect work being reduced to a minimum.

50 To that end my invention consists, essen-

tially, in the combination, with a stationary setting-die, of a reciprocating plunger provided with an intermittently-rotating stud-feeding wheel, a runway working in unison with the plunger and communicating with a 55 fixed runway, along which the lacing-hooks slide downwardly by gravity, and a mechanically-actuated separator located in the runway arranged to hold the column of hooks in check and at the same time adapted to separate 60 the bottom hook from the column and deliver it to the feed-wheel, all as will be more fully hereinafter set forth and claimed.

In the accompanying sheet of drawings, Figure 1 is a side elevation of a machine for 65 setting lacing-hooks and embodying my present improvements, the parts being shown in the normal position preparatory to receiving the work. Fig. 2 is a corresponding front end view. Fig. 3 is an enlarged transverse 70 section taken on line *w w* of Fig. 1. Fig. 4 is a partial side view showing the machine in the act of setting a hook. Fig. 5 is a horizontal section, enlarged, taken on line *x x* of Fig. 4. Fig. 6 is an inverted plan view of the 75 plunger and its attached members. Fig. 7 is a side view of the ratchet-wheel and the upper end of the actuating-pawl, and Fig. 8 is a perspective view of a lacing hook or stud adapted to be employed in my improved setting-machine.

In the drawings, A indicates my improved machine as a whole, the usual reservoir from which the hooks or studs *h* are fed to the runway being omitted. The runway, as shown, 85 is composed of two flat parallel strips of metal *r*, mounted in a vertical plane common to both and separated laterally, thereby forming between them a space *r'*, the lower end of the runway being secured to the front side of 90 the upper part of the frame or bed *a*. The said upper portion of the frame *a* is planed out vertically to receive a reciprocating plunger or head *c*, a front cap or plate *a'* holding it in position laterally. The lower part or 95 base of the frame is provided with a removable die-holder *b'*, in which latter is fixed the setting-die *b*. The upper end of the die forms a center or spur adapted to set the tubular shank portion *h'* of the hooks in the leather 100

or material when the plunger is depressed. The vertical reciprocating movements of the latter are, as drawn, effected by means of a pivoted lever m , to which is jointed a link m' , which in turn is connected with an arm c' of the plunger. (See Fig. 1.) The lever itself may be actuated through the medium of the connection m^2 , adapted to be driven by power in any well-known manner.

10 In the lower part of the plunger is mounted a horizontal revoluble shaft s , to which latter are secured the feed-wheel t and ratchet-wheel u . The front end of said shaft turns in a cap or wheel-guard c^2 , secured to and moving with the plunger. The periphery of the feed-wheel t is provided with a series of suitably-shaped recesses or pockets t' , arranged to receive the heads of the hooks. The said ratchet-wheel u has a series of teeth corresponding in number with the said pockets t' . The hook-pawl n for rotating the ratchet-wheel is jointed to a holder n^2 , having a screw-threaded shank passing through a lug formed on the side of the frame-base. Adjusting-nuts n^3 are used 25 for maintaining the proper relation of the pawl to the wheel, so that at each reciprocation of the plunger the feed-wheel will present a hook centrally over the setting-die. A spring n' serves to keep the pawl in continuous yielding contact with the wheel u . To the front side of said wheel-guard or cap c^2 is secured a strip r' of metal, the same extending upwardly and forming a continuation of the runway r . The hooks h slide downwardly 30 astride the inner edge of the piece r' , the heads thereof fitting into the pockets t' , and are carried around with the wheel t , as shown in Figs. 1, 3, and 5. It will be seen that the eyelet or shank portions of the hooks extend 35 outwardly from the runway and that they are maintained in substantially the same plane from the time the hooks are introduced to the runway until they engage the feed-wheel.

40 At the lower end of the fixed part of the runway r is located a pivotally-mounted flat lever e , which I term a "separator." The head of this lever is circular, its periphery being provided with a notch e^2 , adapted to receive the shank or eyelet portion h^2 of the hooks.

45 The said notch is comparatively small and capable of receiving only one hook at a time. The head portion or flange of the lever is concentric and pivotally mounted on a pin passing through the center of the head, as clearly 50 shown. By means of this construction the hooks supported thereby are not disturbed by the swinging movements of the separator. This result is due to the fact that the periphery of the head is concentric to the pivot on 55 which it swings. The lever is also provided with an arm e' , having its upper side in continuous engagement with a vertically-movable pin d , mounted in an extension or lug a^3 of the frame a , said pin being resisted by 60 a spring d' . (See Fig. 4.) To the lower part of the plunger c is secured a dog f , its upper

end being arranged to contact with the lower side of the arm e' when the plunger is elevated. Thus it will be seen that upon depressing the plunger c the pin d automatically swings the lever-head e upwardly until arrested by the stop-pin s^4 , thereby bringing the notched portion e^2 into position to receive the lowest hook on the runway, the force of the spring d' at the same time holding the entire column of hooks in check, as shown in Fig. 4. Upon the return or upward stroke the dog f forces the arm in a corresponding direction until at the termination of the plunger's movement the notched part of the lever 75 will be open to the runway-groove r^2 below, at which instant the hook drops therefrom by gravity and is caught below in the uncovered pocket or recess of the wheel t . Thus it is seen that the lever or separator e in is movement detaches the bottom hook from the column (shown in Fig. 4) and drops it into the feed-wheel, the periphery of the separator at the same time swinging across the runway-groove and for the time being closing it. (See 80 Fig. 1.) While the upward movement of the plunger is thus taking place, the stationary pawl n will have rotated the ratchet-wheel one tooth, thereby placing a new hook in position 85 above the die. 90

In Fig. 3 I have shown a yielding stop or catch l let into the plunger, the head of the former being adapted to successively engage the pockets t' of the feed-wheel. A spring P insures the action of the catch. This device 95 not only serves to hold the wheel in check while the plunger is making the return stroke, but it also serves to steady it, so that the eyeleted portion of the hooks will be centralized with respect to the spur or tip of the setting-die. 100

In order to maintain the head portion of the hook against the corresponding bent part of the runway member r' , contiguous to the feed-wheel, while the hook is being set, and thus forming an anvil, the plunger is provided on its lower end with a bent check-lever w , a spring w' serving to keep the lever in frictional contact with the hook, all as clearly shown in Fig. 6. 115

In my improved machine the wheel t does not in any manner serve as a spacing-wheel. It is used for mechanically feeding or transferring the hooks singly from the runway to the anvil. The work or material to which 120 the hooks are to be secured is first suitably punched, the holes thus formed being spaced the desired distance apart. Now upon starting the machine the attendant simply places the punched portion of the shoe or material 125 upon the center of the spur or die b , the latter at the same time extending upwardly through the corresponding hole. The action of the plunger in descending then forces the tubular shank h^2 of the bottom hook through the said 130 hole, thereby clenching or upsetting it thereunder. While the plunger is ascending, the

wheel is rotated one notch or space, thus automatically bringing another hook in position, at the same time releasing the one already set from the anvil, followed by setting another hook, as just described.

5 By the use of my improvements the machine may be successfully operated at a comparatively rapid rate of speed from the fact that the attendant is enabled to easily and 10 quickly change the work from hole to hole with respect to the non-movable setting-die *b*.

What I claim as my invention is—

1. In a machine for setting lacing-hooks, the combination with a fixed setting-die and 15 a stationary runway for the hooks, of a vertically-reciprocating plunger provided with a hook-guide forming a continuation of said runway, an intermittently-revolvable feed-wheel mounted in the plunger and communicating 20 with the runway, means for actuating said plunger and feed-wheel, and an oscillating separator controlled by the plunger's movements for transferring the hooks singly and successively from the runway to the feed-wheel, substantially as described.

2. In a machine for setting lacing-hooks, the combination with the fixed setting-die *b*, a stationary die-holder having said die adjustably mounted therein and a stationary 30 runway for the hooks, of the revolvable hook-feeding wheel *t*, a horizontal shaft *s* having said wheel secured thereto, a vertically-reciprocating plunger carrying said shaft and wheel, a vertically-movable runway arranged 35 below and communicating with the said stationary runway and forming an anvil with the feed-wheel for resisting the force exerted in setting the hooks, and means substantially as

described for intermittently rotating the feed-wheel, substantially as set forth.

3. In a machine for setting lacing-hooks, the combination with the stationary setting-die *b* and the fixed runway *r*, along which the lacing-hooks slide, of the vertically-reciprocating plunger member *c* provided with an auxiliary lower runway adapted to communicate with and form a continuation of said fixed runway, a revolvable feed-wheel mounted in the lower end of the plunger provided with a series of peripheral recesses *t* arranged to receive the heads of the hooks therein and coacting with the said lower runway to form a guide for the hooks, a separator device working in a plane parallel with the face of the runway for delivering the hooks singly to the feed-wheel, and yielding stops or holders for maintaining the feed-wheel and its bottom hook in position while the latter is being attached to the boot or shoe, or other material, substantially as hereinbefore described.

4. In a machine for setting lacing-hooks, the combination with the vertically-reciprocating plunger provided with a feed-wheel and lower runway member, of the spring-resistant check-lever *w* pivoted to the plunger 65 for holding the bottom hook in position while it is being set, and the yielding stop or catch *l* in contact with the feed-wheel, substantially as hereinbefore described.

In testimony whereof I have affixed my signature in presence of two witnesses.

STEPHEN N. SMITH.
